UPPER HANDLE MEMBER FOR LAWN MOWERS AND THE LIKE

Mario F. Fernandez and Bruce John Rubin, St. Paul,
and Richard A. Thorud, Minneapolis, Minn., assignors
to The Toro Company, Minneapolis, Minn.

Filed Aug. 10, 1972, Ser. No. 279,379

Term of patent 14 years

Int. Cl. D15—99, 03
U.S. Cl. D40—1 A

FIG. 1

FIG. 2

FIG. 4

FIG. 3

FIG. 1 is a perspective view of a power mower with the upper handle member for lawn mowers and the like embodying our design;

FIG. 2 is a front view thereof;

FIG. 3 is a side view thereof; and

FIG. 4 is a top view thereof.

The broken line illustration of the power mower and lower handle member for lawn mowers and the like is shown for illustrative purposes only.

We claim:

The ornamental design for an upper handle member for lawn mowers and the like, as shown and described.
